PNEUMATIC THREAD HOLDER FOR LOOMS

Richard G. Turner, Worcester, Mass., assignor to
Crompton & Knowles Loom Works, Worcester,
Mass., a corporation of Massachusetts

Application February 27, 1943, Serial No. 477,426

9 Claims. (Cl. 139—247)

This invention relates to improvements in weft replenishing looms and it is the general object of the invention to provide a pneumatic thread holder so constructed as to facilitate removal of the thread of a transferred bobbin.

Weft replenishing looms operate with a group of reserve bobbins from which weft ends extend to a thread holder. At the time of transfer a bobbin is moved from the group to a depleted shuttle and on the subsequent picking operation of the loom the shuttle is picked away from the thread holder. In order to effect threading of the shuttle the thread holder must hold the thread during shuttle flight. On some subsequent pick of the loom the thread extending from the thread holder is cut at the adjacent selvage, after which the thread must be removed to prevent it from being drawn into the warp shed.

When a pneumatic thread holder is employed there is a tendency for the weft ends of the reserve bobbins to cluster together and form a thread mass which holds the thread of the transferred bobbin and interferes with its removal when cut at the selvage. This is particularly true when large or coarse weft is used. It is an important object of my present invention to provide a pneumatic thread holder so constructed as to effect a separation of the thread of the transferred bobbin from the remaining threads in the holder and draw the separated thread across the stream of air moving into the thread holder. The thread of the transferred bobbin may be in close contact with the other threads at the rear part of the thread tube but will become detached from them as it is drawn into and through the thread holder tube.

In order to exert a proper holding force on the weft ends air must be drawn into the intake mouth of the thread holder either at or above a minimum rate which is determined by the rate at which the shuttle travels and the tension exerted on the weft by the fur which lines the shuttle walls. The larger the intake mouth the lower the rate will be for a pump of given capacity and in order to insure a proper rate of movement of air into the intake mouth the latter should be kept as small as possible. When the magazine is full, however, there will be a large number of weft ends leading to the thread holder and the latter must be large enough to accommodate all of the weft ends. In order to provide a thread holder sufficiently large to hold all of the threads of the reserve bobbins and at the same time be sufficiently small to insure the proper rate of motion of air into the mouth it is another object of my invention to form the intake mouth with a relatively large upper part to receive the weft ends from the reserve bobbins in the magazine and form the lower part of the mouth with a reduced area sufficient to receive the thread of the transferred bobbin but not large enough to in-

terfere seriously with the rate at which air moves into the thread holder. The foregoing advantages may be obtained by forming the intake mouth more or less in the shape of a keyhole having a large upper part and a narrow lower part communicating therewith and forming part of the opening into which air is drawn.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is an end elevation of a loom having my invention applied thereto.

Fig. 2 is a front elevation on an enlarged scale looking in the direction of arrow 2, Fig. 1.

Fig. 3 is a horizontal section on line 3—3 of Fig. 2.

Fig. 4 is an enlarged vertical section on line 4—4 of Fig. 2, and

Fig. 5 is a vertical section on line 5—5 of Fig. 4.

Referring particularly to Fig. 1, I have shown a loom frame 10 having a lay 11 which is reciprocated horizontally by connectors 12 driven by the top or crank shaft 13 of the loom. The shaft 13 makes a revolution for each pick or beat of the loom and ordinarily turns in the direction of arrow a. Fixed to the loom frame is a pump 14 having a piston 15 connected to a rod 16 pivoted to the upper end of a lever 17 which is pivoted as at 18 to the loom frame. A connector 19 extends between the lay 11 and the lever 17 and causes the latter to reciprocate with the lay so that the piston 15 moves to the right as viewed in Fig. 1 while the lay is moving to the right or rearwardly on its backward stroke, thereby creating a partial vacuum in that part of the pump to the left of the piston 15.

A bracket 20 supported by the loom frame extends outwardly from the latter and affords support for a base 21 which carries a cylinder 24 the upper end of which is closed by a cap 25. A tube 26 extends from the left end of pump 14 to the cap 25 and is the means by which a partial vacuum is created within the cylinder 24 when the lay moves rearwardly. A rod 27 extends upwardly through the cylinder from the base 21 to hold the cap and the base is provided with a recess 28 communicating with the interior of the cylinder. A tube 29 is located within the recess 28 and as shown in Fig. 3 extends to the left through a boss 30 formed on the base 21. A set screw or other means 31 may be employed to hold the tube 29 in fixed position in the boss 30.

The magazine M is pivotally mounted at 35 on a stand 36 mounted on the loom frame and is provided with front and rear stacks of reserve bobbins 37 and 38, respectively, which feed downwardly by gravity. A transfrer arm 39 is pivotally mounted at 40 to the stand 36 and

is pivotally mounted at 41 to the magazine M. The transfrer arm 39 is provided with a hook 42 which is pivotally mounted at 43 to the magazine M and is provided with a hook 44 which is pivotally mounted at 45 to the rear stack of bobbins 38. The hook 44 is provided with a slot 46 which receives the end of the hook 42 when the magazine M is pivoted to the rear so that the hook 44 is moved into the slot 46.

is provided with the usual transfer latch 42 for engagement with the bunter 43 on the lay. The latch is ordinarily in its down inoperative position as shown in Fig. 1 and the transerrer arm is raised. Whenever a replenishing operation of the loom occurs, the latch 42 is raised by well-known mechanism not shown into the path of a lay carried bunter 43 and the transerrer arm is given a downward motion as the lay moves forwardly. During transfer the transerrer arm will engage the lowest bobbin in the stack which is in transfer position. As shown in Fig. 1 the front stack 37 is in transfer position so that its lowest bobbin is in the path of the transerrer arm and will be inserted into a shuttle S on the lay. The magazine can, however, be rocked by mechanism designated generally at 44 to place the lowest bobbin in the rear stack 38 under the transerrer arm.

As shown in Fig. 2 the bobbins B are each provided with weft ends W which extend away from the magazine toward a thread holder designated generally at H. As shown in Fig. 2 the lowest bobbin B' of the stack 37 has its weft end W at the bottom of the group of weft threads associated with the bobbins in the magazine. When this bobbin is transferred into the shuttle S it will move downwardly to the position indicated at W2 in Fig. 2 and the weft will then be separated from the aforesaid group of threads and may extend upwardly toward the thread holder as shown in Fig. 2. All of the weft ends extend into the previously described tube 29 and become wrapped around the rod 21 to form a yarn mass Y as indicated in Fig. 3. This mass of yarn serves as an anchorage for the weft ends and operates in addition to the pneumatic pressure of the thread holder to hold the threads in tube 29. On some pick subsequent to transfer the thread of the freshly transferred bobbin will be cut at the adjacent selvage not shown and will be free to respond to any pneumatic force exerted on it.

The matter thus far described, except as noted hereinafter, may be of usual construction as set forth in my prior Patents Nos. 2,199,353 and 2,199,354.

It will be apparent from Fig. 2 that the group of threads W lead downwardly from their respective bobbins to the thread tube 29 and are therefore likely to extend along the upper part of the tube. The latter may be inclined upwardly and toward the magazine as shown in Fig. 5 so that the several ends will be distributed as indicated in the upper part of Fig. 4 and located in the relatively wide upper end 50 of the intake mouth designated generally at 51. As the threads enter the left end of the tube 29 they will be held more or less in spaced relation with respect to each other but are likely to be clustered together as indicated at 52 at the right end of the tube 29 as viewed in Fig. 5 when passing out of the tube toward the interior of the cylinder 24. When the weft ends are of large diameter and soft they pack into a mass at 52 and tend to stick to each other. It should be noted that the threads of the highest bobbins in the magazine are likely to engage the upper part of the tube 29 near its intake mouth or at the left end of Fig. 5, but as the bobbins descend in the magazine their weft ends become more and more nearly horizontal and become detached from the mass of threads at the top of the tube 29 as they move downwardly into the part 50 of the intake mouth, as indicated in Fig. 4.

Communicating with and depending from the part 50 of the intake mouth is a narrow slot 55 small enough to add very little to the cross-sectional area of the intake mouth but wide enough to receive a single thread. As the bottom of the lowest bobbin of the stack in transfer position is moved from the magazine into the shuttle its thread will descend as suggested at W2 in Fig. 2 and will enter the narrow slot 55 and become completely detached from the group of threads in the upper wider part 50 of the intake mouth. This thread W2 will extend to the right end of tube 29 as shown in Fig. 5 and will be in contact with the other threads of the thread holder, but it will be seen that the thread W2 extends across the stream of air passing in the direction of arrow b in tube 29 and will therefore be subject to the maximum pneumatic force of the stream of air. When the shuttle is picked the thread of the freshly transferred bobbin retains its low position and will be caught at the selvage on the next forward beat of the lay. When thread W2 is subsequently cut the column of air moving to the right through tube 29 as viewed in Fig. 5 will move the thread into the tube and have the effect of detaching it from the group at 52 so that the thread can pass completely into the cylinder 24.

In the past it has been customary to form the intake mouth in a substantially circular form, but because of the requirement that it be as small as possible in order to insure an adequately high rate of air flow through the tube 29, the thread of the transferred bobbin has not been able to detach itself sufficiently from the other threads. As shown herein, however, the narrow slot 55 enables the thread of the transferring bobbin to detach itself from the group without adding materially to the cross-sectional area of the intake mouth and the rate of air moving into the tube 29 is sufficiently high to effect removal of the thread when it is cut.

From the foregoing it will be seen that I have provided a simple form of thread holder the intake mouth of which is so formed as to insure a proper rate of flow of air through the tube 29 at the same time enable the thread of the transferred bobbin to detach itself from the other threads in the tube and extend across the stream of air rushing into the intake mouth. It will also be seen that as the bobbins descend in the magazine their threads tend to move downwardly into the wide upper part 50 of the intake mouth in preparation for the final separation from the group of the threads of the transferred bobbin. While my invention is useful with all sizes of yarns it has particular value in the weaving of fabrics requiring coarse weft.

Having thus described my invention it will be seen that changes and modifications may be made therein by those skilled in the art without departing from the spirit and scope of the invention and I do not wish to be limited to the details herein disclosed, but what I claim is:

1. In a pneumatic thread holder for a weft replenishing loom having a group of reserve bobbins and having provision for moving a bobbin downwardly from the group into a shuttle below the group, said bobbins having weft ends extending therefrom, a pneumatic thread holder tube into which a draft of air is drawn to attract the weft ends into the tube, said tube having an end thereof facing the bobbins and provided with an intake mouth the upper part of which is relatively large to receive the weft ends

from the bobbins in said group and the lower part of which is restricted to receive the weft end of a bobbin in the shuttle.

2. In a pneumatic thread holder for a weft replenishing loom having a group of reserve bobbins and having provision for transferring a bobbin downwardly from the group into a shuttle below the group, said bobbins having weft ends extending therefrom, a pneumatic thread holder tube having an intake mouth into which a draft of air is drawn for the purpose of attracting said weft ends through said mouth and into the tube, said intake mouth having a wide relatively large upper part to receive the weft ends from the bobbins in said group communicating with a relatively narrow lower part of the mouth so positioned as to receive the weft end of a bobbin transferred from the group into said shuttle.

3. In a pneumatic thread holder for a weft replenishing loom having a group of reserve bobbins and having provision for transferring a bobbin downwardly from the group into a shuttle below the group, said bobbins having weft ends extending therefrom, a pneumatic thread holder tube having a mouth into which a draft of air is drawn for the purpose of attracting said weft ends through the mouth and into the tube, said mouth having an upper part which is relatively large to receive the weft ends of the bobbins in said group, the tube so located that the last named weft ends lead along the upper part of said tube, and said mouth having a relatively narrow downwardly extending part communicating with said large part of the mouth to receive the weft end of a bobbin transferred from the group into said shuttle and cause the last named weft end to extend diagonally across the interior of said tube from a point adjacent to said narrow part of the mouth to a point adjacent to the upper part of said tube.

4. In a pneumatic thread holder for a weft replenishing loom having a group of reserve bobbins and having provision for transferring a bobbin downwardly from the group into a shuttle below the group, said bobbins having weft ends extending therefrom, a hollow thread holder tube having an intake mouth into which a column of air is drawn for the purpose of drawing said weft ends pneumatically through said intake mouth and into the tube and causing the weft ends to lie along the upper part of said tube, said intake mouth having a relatively wide upper part communicating with a relatively narrow lower part thereof, the weft ends from the bobbins in said group extending into the relatively wide part of said mouth and the weft end of a bobbin transferred from said group into said shuttle extending downwardly into the narrow part of said mouth and extending from the latter diagonally upwardly toward the weft ends located at the upper part of said tube.

5. In a pneumatic thread holder for a weft replenishing loom having a group of reserve bobbins and having provision for transferring a bobbin downwardly from the group into a shuttle below the group, said bobbins having weft ends extending therefrom, a hollow thread holder tube having an intake mouth into which a column of air is drawn for the purpose of drawing said weft ends pneumatically through said

intake mouth and into the tube, said intake mouth being so shaped that the weft ends from the upper bobbins in said group enter a relatively wide upper part of said intake mouth and the weft ends of the bobbins in the lower part of said group enter said relatively wide part of the mouth at points below the weft ends of the upper bobbins in the group to effect a partial separation of said weft ends in the upper part of said mouth as the bobbins move downwardly in a group, and said intake mouth having a relatively narrow depending part communicating with said upper part to receive the weft end of a bobbin transferred into said shuttle and locate the last named weft below the weft ends of the bobbins in said group.

6. In a pneumatic thread holder for a weft replenishing loom having a group of reserve bobbins and having provision for transferring a bobbin downwardly from the group into a shuttle below the group, said bobbins having weft ends extending therefrom, a pneumatic thread receiver comprising a hollow member within which a partial vacuum is created, a tube one end of which communicates with the interior of said hollow member and the other end of which is formed with an intake mouth facing said bobbins and into which a column of air moves due to the partial vacuum in said hollow member, said intake mouth having an upper part of relatively large cross sectional area to receive the weft ends of the bobbins in said group and from which the last named weft ends extend along the upper part of said tube in a group to the interior of said hollow member, and said intake mouth having a lower part of less cross sectional area than that of said upper part of the mouth to receive the weft end of a bobbin transferred from the group into said shuttle, the last named weft end extending upwardly from said lower part of the mouth and diagonally across the interior of said tube to said hollow member and in the path of said column of air to be detached by the latter from said group of threads at the top of said tube.

7. A thread receiving tube for a weft replenishing loom pneumatic thread holder, said tube having one end formed to define an intake mouth the upper part of which has a relatively large cross sectional area and the lower part of which has a relatively small cross sectional area communicating with said upper part.

8. A thread receiving tube for a weft replenishing loom pneumatic thread holder, said tube having a body the greater part of which is of cylindrical form but one end of which is constructed to have a thread receiving intake mouth the upper part of which is of substantial circular cross section of less diameter than the diameter of the tube and the lower part of which is provided with a vertically extending narrow part the cross sectional area of which is less than the cross sectional area of said upper part.

9. A thread receiving tube for a weft replenishing loom pneumatic thread holder comprising a hollow body one end of which is formed with a substantially keyhole-shaped intake mouth having an upper wide part communicating with a lower narrow part.

RICHARD G. TURNER.
